UNITED STATES PATENT OFFICE

ALBERT C. WALDVOGEL, OF RICHMOND HEIGHTS, MISSOURI

PUNCH PRESS

Application filed January 16, 1930. Serial No. 421,100.

The invention relates to a punch press particularly applicable for use in punching a continuous succession of holes or notches in a continuous ribbon of material.

5 The principal object of the invention is to provide such a punch press which may be simply and economically built and which will operate at a high rate of speed.

The principal feature of the invention re-10 sides in the provision of means for continuously feeding a strip of material through the machine together with movable punching mechanism for punching a series of holes or notches in the said strip while passing there-15 through, the punching mechanism moving with the strip of material during each punching operation and returning to initial position when said operation is completed.

Another feature resides in the fact that the 20 movement of the punching mechanism is accomplished by pull of the strip of material when engaged with the punch.

Other objects and features of the invention will be more fully understood from the 25 accompanying drawings and the following description and claims:

Fig. 1 is an elevational view of the end of the apparatus to which the ribbon of material is admitted. Fig. 2 is an elevational 30 view of the opposite end of the apparatus. Fig. 3 is a central elevational section thereof.

A base casting 10 supports a frame member 11 upon which is formed a worm gear housing 12. A worm shaft 13 is journaled 35 in the said housing and carries a worm 14 adapted to engage a worm wheel 15. The worm wheel 15 is mounted upon a shaft 16 journaled in the frame member 11. The gear housing 12 is closed by a cover member 17 40 forming a second bearing for the shaft 16. The frame member 11 also supports in suitable bearings a shaft 18 carrying a roller 19. A second roller 20 is positioned directly 45 above the roller 19 and is supported upon a shaft 21. The ends of the shaft 21 are carried in vertically slidable bearing members 22 mounted upon the frame member 11. The cover member 17 carries a pair of projecting arms 23 threadedly engaging vertical stems 50 24. Each of the stems 24 carries at its lower

end a flange 25. A compression spring 26 is interposed between each of the flanges 25 and one of the bearing members 22. The upper end of each of the stems 24 terminates in a head 27 through which is inserted a pin 28 55 for rotation of the stem. A lock nut 29 is carried by each stem 24 adjacent the corresponding arm 23. By this means the roller 20 is maintained in yielding engagement with the roller 19 and the pressure of said engagement may be adjusted by turning the stem 24 and may be maintained by means of the lock nut 29.

The base casting 10 carries a pair of upright supporting members 30 in turn carrying a transverse shaft 31 journaled therein. A yoke member 32 is supported upon said shaft and in turn supports a pair of downwardly-extending parallel bolts 33. At the lower end of the said bolts a yoke member 34 is supported by means of nuts 35. A substantially rectangular casting 36 is slidably mounted upon the bolts 33 and is supported by means of compression springs 37 interposed between said casting and the yoke 75 member 34.

The shaft 16 carries a flanged coupling 38 and a mating coupling 39 is fastened thereto and carried by a short shaft 40 in turn supported upon bearing members 41 extending 80 between the upright members 30. A cam 42 having a plurality of projecting portions 43 is carried upon the shaft 40 between the bearing members 41 and is positioned within an opening 44 in the casting 36. A ball or roller 45 is carried in a suitable cup in the casting 36 and is adapted to engage the cam 42. It will be noticed in Fig. 3 that the surface of the cam projections 43 is formed on the arc of a circle having its center at the center of shaft 90 31 when said projections are in their lowermost position. Thus, the yoke 32 and the members carried thereby may swing about the shaft 31 without disturbing the contacting relation between the said cam and the ball or roller. The casting 36 carries upon its lower surface a punch-holding member 46 herein illustrated as carrying a pair of punch members 47. A die block 48 is carried by the yoke member 34 and is fitted with die open- 95 100

ings not shown for cooperating with the punches 47. A stripping plate 49 is carried upon the die member 48 and is formed with openings 50 therein through which the ribbons of material to be punched may be passed.

5 A cord 51 is attached to the die member 48 and passes over a pulley 52 supported upon the base casting 10. A counterweight 53 is hung upon the downwardly-extending portion of the cord 51. An adjustable stop member 54 is supported upon the base casting 10 and is adapted to contact with the yoke member 34.

In the operation of the device, a pair of ribbons of material 55 are threaded through the openings 50 and between the rollers 19 and 20. The shafts 13 and 18 are then rotated by any suitable power means, the ribbons of material are continuously drawn through the machine and the cam member 42 is rotated. When one of the cam projections 43 engages the ball or roller 45, the casting 36 and the punches 47 carried thereby are forced downwardly until the punches engage the ribbon 25 of material. When this engagement takes place, the yoke member 32 and the members carried thereby are drawn by the ribbon of material to the right as illustrated in Fig. 3, the counterweight 53 being raised. Further rotation of the cam 42 forces the punches 47 through the material, cutting the desired holes or notches therein. When the cam projection 43 is disengaged from the ball or roller 45, the springs 37 force the castings 36 and 35 punches 47 upward to disengage the punches from the material. The counterweight 53 then returns the swinging members to initial position with the yoke 34 resting against the stop member 54. The cycle is repeated by 40 continued rotation of the shafts 13 and 18 and a succession of notches or holes is thereby punched in the ribbons of material.

The apparatus herein described is particularly applicable for punching notches in a ribbon of drawn spring steel to be used for the internal expanding ring for automotive pistons but is equally applicable to a wide variety of other uses. The apparatus may be used in tandem with other machines or made 45 a part of machines performing other operations upon the ribbon of material. When so used, the couplings 38 and 39 are made radially adjustable with respect to each other so that the punching operation may be adjusted 50 with relation to other operations upon the ribbon.

The invention claimed is:

1. A punch press including a supporting frame, mechanism for continuously supplying a ribbon of material to be punched, punching elements pivotally suspended from a portion of said frame, a shaft carried upon another portion of said frame, a cam carried by said shaft, and a rotatable member carried 55 by one of said punching elements and adapted

to engage said cam for bringing said punching elements into punching relation with the ribbon of material, said cam being shaped to engage said rotatable member independently of the motion of said punch members about their pivotal mounting.

2. A punch press including a supporting frame, mechanism for continuously supplying a ribbon of material thereto, punching elements pivotally mounted upon a portion of said frame, a shaft rotatably mounted upon another portion of said frame, a cam carried by said shaft and adapted to engage one of said punching elements for bringing the same into punching relation with said ribbon of material, said cam being shaped to make said engagement independently of the movement of said punching elements upon their pivotal mounting.

3. A punch press including a supporting frame, a horizontal shaft supported thereon, a second frame pivotally mounted upon said shaft and hanging beneath the same, said frame including a pair of spaced-apart rods and a yoke member carried upon the lower ends thereof, a punch member vertically slideable upon said vertical rods, a die member carried by said yoke and adapted to cooperate with said punching member, mechanism for continuously feeding a ribbon of material between said die and punch members, a horizontal shaft extending between said vertical rods, a cam carried by said last-mentioned shaft and having protuberances adapted to engage said punch member for forcing the same downwardly to engage and punch said ribbon, said pivotally-mounted frame and members carried thereby being movable by and with said ribbon in the punching operation, and means for returning said frame to initial position upon the completion of punching.

4. A punch press including a supporting frame, mechanism for continuously supplying a ribbon of material thereto, punching elements pivotally mounted upon a portion of said frame, a shaft rotatably mounted upon another portion of said frame, the axis of said shaft lying in a plane transverse to the axis of the pivotal mounting of said punching elements, a cam carried by said shaft and adapted to engage one of said punching elements for bringing the same into punching relation with said ribbon of material, said cam being shaped to make said engagement independently of the movement of said punching elements upon their pivotal mounting.

In witness whereof, I have hereunto affixed my signature.

ALBERT C. WALDVOGEL.
